Inventor,
Edward B. Weston

UNITED STATES PATENT OFFICE.

EDWARD B. WESTON, OF DAYTON, OHIO.

DESIGN FOR A FRAME FOR ROLL-PAPER HOLDERS AND CUTTERS.

SPECIFICATION forming part of Design No. 25,761, dated July 7, 1896.

Application filed May 6, 1895. Serial No. 548,341. Term of patent 7 years.

To all whom it may concern:

Be it known that I, EDWARD B. WESTON, a citizen of the United States, and a resident of Dayton, in the county of Montgomery and State of Ohio, have invented and produced a new, useful, and original Design for Frames for Roll-Paper Holders and Cutters, of which the following is a full, clear, and exact description, reference being had to the accompanying drawing, forming part of this specification.

In the drawing is shown a perspective view of my design with a roll of paper in place.

A is the base; B B, the standards; C, the cutter-blade; D D, the supporting-arms for same, and E the top piece.

The feature of my design consists in the fluted standards or supports, as shown in the drawing, and also in the fluted supporting-arms of the cutter-blade.

Having thus described my invention, what I claim, and desire to secure by Letters Patent, is—

The design for a frame for a roll-paper holder and cutter, substantially as herein shown and described.

EDWARD B. WESTON.
